UNITED STATES PATENT OFFICE.

JEREMIAH J. FITZPATRICK, OF TULSA, OKLAHOMA, ASSIGNOR TO EAGLE MANUFACTURING ASSOCIATION, ORGANIZED UNDER A DECLARATION OF TRUST.

INTAKE FOR OIL-WELL PUMPS.

Application filed February 5, 1923. Serial No. 617,178.

To all whom it may concern:

Be it known that I, JEREMIAH J. FITZPATRICK, a citizen of the United States, residing at Tulsa, in the county of Tulsa and State of Oklahoma, have invented certain new and useful Improvements in Intakes for Oil-Well Pumps, of which the following is a specification.

This invention relates to intakes for oil well pumps.

An object of the invention is the provision of an intake that will permit water and oil to be pumped from a well without pumping an appreciable quantity of sand.

A further object is to provide an intake, that is a sand and gas eliminator, arranged entirely below the working barrel, whereby the sand and gas will be kept away from the valves and valve seats in the working barrel.

A further object is to provide an intake that permits the law of gravity to function in the separation of sand and gas from oil and water and having no valves therein, the life of the intake is prolonged.

In the accompanying drawings, I have shown one embodiment of the invention. In this showing:

Figure 1 is a front elevation of the device in position within a well.

Figure 2 is a vertical view.

Figure 3 is a horizontal view on line 3-3 of Figure 2.

Figure 4 is a horizontal sectional view on line 4-4 of Figure 2, and,

Figure 5 is a similar view on line 5-5 of Figure 2.

Referring to the drawings, the reference numeral 1 designates the lower end of a working barrel, arranged within a well. This working barrel is provided with the usual standing valve 2 at the bottom, and traveling valve 3 above the standing valve.

The apparatus forming the subject matter of the present invention consists of an enlarged bowl or casing 4 having reduced upper end 5. This upper end is threaded and is adapted to receive the collar of the lower section of the working barrel. The lower end of the bowl is provided with a threaded portion on the inside 6, adapted to receive pipe 11. The upper portion of 7, being the lower portion of the bowl, is provided with a plurality of concave recesses 8, extending downwardly from near the bot-

tom of the bowl and communicating with the interior of pipe 11. The recesses are provided with inner walls 9. The bottom 9 of the bowl 4 is threaded on the inside 10 to receive intake pipe 12. As shown in Figure 2, the intake pipe 12 extends upwardly within the bowl 4. The lower end of pipe 11 is swaged or bushed down, and threaded on the inside to receive plug 13 or to attach anchor pipe or to be left open according to the status of the oil well.

The pipe 11 is perforated at 14, above the bottom 13 and below the bottom of intake pipe 12 to allow the water to be pumped below the recesses 8 or to be closed according to the oil well.

The working barrel is arranged in a well 15 with the intake disposed beneath it. It will be apparent that the valves and valve seats are arranged above the intake and the sand and gas separated from the water and oil by the downward motion of the fluid from recesses 8 to the bottom of intake pipe 12 and in the bowl 4 before it reaches any valves and valve seats, thus minimizing wear on these parts and the working barrel proper, due to the cutting effect of particles of sand and unseating the ball in the standing valve by gas pressure.

When the pumping operation is first started if the oil well is making some water, the water passes through the recesses 8 until the water is pumped to the level thereof, then it enters the perforation 14 until it is pumped below the bottom of intake pipe 12 and as the oil is always on top of the water, then it will pump oil, as it will pump only the fluid that the bottom of the intake pipe 12 is submerged in. As the oil passes through the recesses 8 it is given the downward motion until it reaches the bottom of the intake 12 and any sand that is heavier than oil or water will keep on going downward by the law of gravity.

The fluid is then taken up in the bowl 4 through the intake pipe 12 and there being a volume of fluid lying dormant to enter the working barrel, any sand that may have reached the bowl 4 would settle around the outside of the intake pipe 12 in the bowl 4 as shown in Figure 2. As there is no rush of oil at any time within the intake, all the openings being many times larger than the opening in the valve seat of the standing valve 2, it allows plenty of time for the law of gravity to function and elimi-

nates the breathing effect common to devices now in use.

The flood hole 16 in the top of the bowl 4 is for the purpose of the working barrel receiving air whenever the fluid is pumped down to that level, thereby keeping whatever portion of the oil sand covered with oil as is desired.

The oil never enters the perforation 14 on account of the cushion of water lying in the bottom of the well and in casing 11 just below the intake pipe 12, but always enters at the recesses 8. With proper installation of this intake the water can be pumped from the bottom of the well first and keep the oil sand covered with oil in place of water, which would have a tendency to increase oil production and raise the gravity of the oil.

In a vast majority of oil wells this plug 13 in the bottom of casing 11 would be left out which would allow the sand to siphon down the inside of casing 11 and pipe 12 and out through the opening 13 to the bottom of the well.

It is to be understood that the form of the invention herewith shown and described is to be taken as a preferred example of the same and that various changes in the shape, size, construction and arrangements of parts may be resorted to without departing from the spirit of the invention or the scope of the subjoined claims.

Having thus described my invention, I claim:

1. An intake for oil well pumps comprising a casing adapted to be arranged on the lower end of a working barrel, said casing being of greater cross-sectional area than the cross-sectional area of said working barrel, the lower end of said casing being provided with an opening of reduced cross-section, an intake pipe adapted to be arranged in said opening, the lower end of

said casing being provided with spaced recesses surrounding said opening, and a casing surrounding said intake pipe and secured to the lower end of said first casing whereby communication with the interior of said second casing is permitted through said recesses.

2. An intake for oil well pumps comprising a casing adapted to be arranged on the lower end of a working barrel, said casing being of greater cross-sectional area than the cross-sectional area of said working barrel, the lower end of said casing being provided with a central opening of reduced size, an intake pipe arranged in said opening and depending from said casing, said casing being further provided with a plurality of spaced concave recesses extending upwardly from the bottom, and a second casing surrounding said intake pipe and secured to said first casing adjacent said recesses.

3. An intake for oil well pumps comprising a casing adapted to be arranged on the lower end of a working barrel, said casing being of greater cross-sectional area than the cross-sectional area of said working barrel, the lower end of said casing being provided with a central opening of reduced size, an intake pipe arranged in said opening and depending from said casing, said casing being further provided with a plurality of spaced recesses extending upwardly from the bottom and a second casing surrounding said intake pipe provided with openings near the bottom thereof and secured to said first casing adjacent said recesses substantially as described.

In testimony whereof, I affix my signature in presence of two witnesses.

JEREMIAH J. FITZPATRICK.
